UNITED STATES PATENT OFFICE.

CHARLES DAVID BONSALL, OF PITTSBURGH, PENNSYLVANIA, ASSIGNOR TO P. H. MURPHY COMPANY, OF NEW KENSINGTON, PENNSYLVANIA.

CAR ROOF.

Original application filed October 2, 1920, Serial No. 414,302. Divided and this application filed September 17, 1924. Serial No. 738,144.

To all whom it may concern:

Be it known that I, CHARLES DAVID BONSALL, a citizen of the United States, and a resident of the city of Pittsburgh, county of Allegheny, and State of Pennsylvania, have invented a new and useful Improvement in Car Roofs, of which the following is a specification.

The subject-matter hereof is divided out 10 of my pending application Serial Number 414,302, filed October 2, 1920, for patent for car roofs.

The present invention relates to car roofs of the all steel riveted type wherein heavy 15 gage self-supporting roof sheets extend from side to side of the car, the roof sheets being rigidly secured together along their side margins and their eaves portions being rigidly secured to the side plates of the car. The 20 principal object of the specific construction claimed herein is to simplify the design of the individual roof sheets that are assembled into a construction embodying the invention set forth in my said pending application; 25 and the present invention consists mainly in a car roof wherein the roof sheets are of channel section and arranged in two series with their side flanges rigidly secured together, the sheets of one series having their 30 channels opening downwardly and alternating with the sheets of the other series whose channels open upwardly.

In the accompanying drawing,

Fig. 1 is a plan view of a car roof embodying the present invention;

Fig. 2 is a vertical longitudinal sectional view thereof on the line 2—2 of Fig. 1;

Fig. 3 is a partial vertical longitudinal sectional view on the line 3—3 of Fig. 1; 40 and

Fig. 4 is a vertical cross-section on the line 4—4 of Fig. 1.

Like reference numerals in the accompanying drawing refer to like parts wherever they occur in said drawing and also in the drawing forming part of my said co-pending application.

The present roof is applied to a steel box car having a roof substructure comprising 50 metal angle-bar side plates 20, which are arranged with one flange up and facing outwardly. A steel car end 21 whose upper portion is flanged inwardly, as shown at 22, and is inclined downwardly on opposite sides of

the ridge to conform to the pitch of the roof, 55 has its upper portion connected to the end of the angle-bar side plates in any desired manner. An angle-bar end plate 23 slopes downwardly on opposite sides of the ridge and has its vertical flange riveted or otherwise rigidly secured to the steel car end 21.

Transversely arranged load - sustaining roof sheets 25^b span the car from side plate to side plate with their eaves portions supported on the upper flanges thereof. The roof sheets slope downwardly on opposite sides of the ridges to form a pitch (or arculate) roof and are made in the form of channels. The roof sheets are arranged in two series, the sheets of one series alternating with those of the other series. The sheets of one series are arranged with the channel 32 opening upwardly and the sheets of the other series are arranged with the channel 31 inverted or opening downwardly. The depending side flanges 29 of the inverted channels overlap the upstanding side flanges 30 of the upwardly opening channels, and said flanges 29, 30, are rigidly secured together by rivets 33 or other suitable means. 60 The body portions of the roof sheets of one series are in a lower plane, while the body portions of the sheets of the other series are in an upper plane substantially parallel with said lower plane. By this arrangement, the 65 neutral plane axis of the roof is approximately midway between said upper and lower planes. The lower plane sheets rest flatwise on the upper flange of the side plate and are riveted or otherwise secured thereto, as indicated at 37; and the end portions of 70 the upper plane sheets are curved downwardly to the plane of the lower sheets at the eaves. The ends of the roof sheets overlap the side plate and end in a downturned flange 35 immediately beyond said side plate.

Running boards 39 rest on and are secured to the horizontal top flanges of angle-bar running board saddles 40 whose vertical flanges are arranged flat-wise against the depending side flanges 29 of the upper plane sheets and are secured in position by means of the rivets 33 that secure together the lapped flanges 29 and 30 of adjacent sheets.

The body portion of the end sheet 42 lies in the plane of the bottoms of the upwardly opening channels of the main sheets 25^b and rests on and is secured to the outwardly pro-

jecting flange of the end angle 23 by rivets 45. The outer margin of the end sheet is turned down over the outer edge of the angle 23 in the form of a drip flange 46.

5 The running boards 39 project beyond the end of the car and have an angle iron 47 bolted or otherwise rigidly secured to the undersides thereof. The overhanging ends of the running boards are braced and supported from the steel car end by means of inclined braces 48 which have their upper and lower ends riveted or otherwise secured to the vertical flange of the angle 47 and the car end 21, respectively.

15 The sheets 25^b are formed of rectangular sheet metal blanks. The surplus metal resulting from decreasing the height of the upper plane sheets in the region of the eaves is used to increase the width of said sheets 20 at the eaves and form an overlap 36 above the lower plane sheets. The eaves end portions of the upstanding side flanges 30 of the lower plane sheets are flattened out over the side plates in the plane of their body 25 portions, as at 34, to bear flatwise on the tops of the side plates. The accompanying drawing illustrates the upper plane sheets as increasing in width from the ridge to each eaves and the lower plane sheets decreasing in width from the ridge to the 30 eaves; but while this particular form has special advantages, it is obvious that the width of the sheets may be uniform from end to end.

35 What I claim is:

1. A car roof comprising a series of sheets extending from eaves to eaves and arranged alternately in upper and lower planes over

the body of the car, the upper plane sheets being inclined downward at the eaves into 40 the plane of the lower sheets, and upturned and downturned side flanges respectively on the lower and upper plane sheets rigidly secured to each other.

2. A car roof comprising a series of roofing sheets extending from eaves to eaves and alternately arranged in upper and lower planes substantially parallel to each other over the body of the car, the upper plane sheets being curved downward at the eaves 45 into substantially the plane of the lower sheets, upwardly and downwardly extending side flanges respectively on the lower and upper plane sheets lying adjacent to each other and riveted, side plates, and means for 50 rigidly securing said sheets at the eaves to 55 said side plates.

3. A car roof comprising a series of roofing sheets extending from eaves to eaves and arranged alternately in upper and lower 60 planes substantially parallel over the body portion of the car, said lower and upper plane sheets having respectively upwardly and downwardly extending side flanges rigidly secured to each other, each of said sheets 65 being formed of a rectangular sheet metal blank and the upper plane sheets being inclined downward adjacent to the eaves into substantially the plane of the lower sheets and the surplus metal being disposed in increased width at the eaves forming an overlap, side plates, and means for rigidly securing said sheets to said side plates.

Signed at St. Louis, Mo., this 15th day of September, 1924.

CHARLES DAVID BONSALL.
